UNITED STATES PATENT OFFICE.

RICHARD T. CRANE, OF CHICAGO, ILLINOIS.

DESIGN FOR A HAND-WHEEL FOR STEAM-VALVES.

SPECIFICATION forming part of Design No. 17,868, dated November 8, 1857.

Application filed September 23, 1887. Serial No. 250,532. Term of patent 14 years.

To all whom it may concern:

Be it known that I, RICHARD T. CRANE, a citizen of the United States, residing at Chicago, in the county of Cook and State of Illinois, have invented and produced a new and original Design for Hand-Wheels for Steam-Valves, of which the following is a specification, reference being had to the accompanying drawings, forming part thereof, in which—

10 Figure 1 is a plan view of my newly-designed hand-wheel; Fig. 2, a side elevation of the same; and Fig. 3, a sectional view taken on the line 1 1 of Fig. 1.

Like letters refer to like parts in all the figures of the drawings.

15 The hand-wheel, formed according to my design, is provided with a central hub, A, from which radiate arms B, which unite with the rim C. This rim is circular in form and curves 20 first upward, then outward, and then downward, being in fact a curved circular hollow rim presenting its concavity downward and its convexity upward. Through the upper part of this rim is a series of radial slots, c, 25 thus leaving a series of arching arms, c', which

form an open-work intermediate portion connecting the outer continuous portion, C', of the rim with the inner continuous portion, C², thereof, to which latter portion the arms B are connected.

A series of depressions, c², may be formed in the outer periphery of the rim C, and in the present instance I have shown these depressions as located at the outer end of each alternate arm c'.

What I claim is—

The design for a hand-wheel for steam-valves, the same consisting of a central hub arms radiating therefrom, and a circular hollow curved rim convex on its upper side and concave on its under side, the said rim consisting of an inner and an outer continuous portion connected by an intermediate open-work portion, substantially as described and shown.

RICHARD T. CRANE.
